CORD CONNECTOR FOR TELEPHONE INSTRUMENTS

Ernest S. McLarn, Manhasset, N. Y., assignor to
 International Standard Electric Corporation,
 New York, N. Y., a corporation of Delaware

Application December 11, 1942, Serial No. 468,605

8 Claims. (Cl. 179—101)

1

This invention relates to telephone handsets and more particularly to means for connecting a multi-conductor cord to the transmitter and receiver units of such handsets.

An object of the invention is to provide an inexpensive, simple and efficient means for connecting the so-called tip-less cordage to telephone handsets not especially designed for use with such cordage.

In my copending application Serial No. 438,774 filed April 13, 1942, patented Oct. 3, 1944, No. 2,359,570, there is disclosed a telephone handset provided with a so-called tip-less cord which is threaded in a channel formed in the handset shell and extending down the handle from the transmitter cavity to the receiver cavity. The transmitter and receiver capsules are provided with connectors formed with sharp prongs which pierce the cord and make electrical connection with the proper stranded conductors when the transmitter and receiver caps are screwed down. It will be appreciated that this construction necessitates the use of specially constructed transmitter and receiver capsules or elements. It is therefore, another object of the present invention to provide adapter devices which will permit the use of standard transmitter and receiver capsules not equipped with the pronged connectors in a handset of the kind employing a continuous tip-less cord extending between the transmitter and receiver cavities.

These and other objects and features of the invention will be clear from a reading of the following description in conjunction with the accompanying drawings in which:

Fig. 1 is a plan view of a handset with the transmitter and receiver caps removed and the handle broken away.

Fig. 2 is a partial section of the transmitter end on the line 2—2 of Fig. 1.

Fig. 3 is a partial section of the transmitter end taken on the line 3—3 of Fig. 1 but also showing the cap and the transmitter capsule.

Fig. 4 is a plan view of the molded transmitter insert.

Fig. 5 is a partial section of the receiver end on the line 5—5 of Fig. 1.

Fig. 6 is a partial section of the receiver end taken on the line 6—6 of Fig. 1 but also showing the cap and the receiver capsule.

Fig. 7 is a plan view of the molded receiver insert.

Referring first to Figs. 1 to 4, the handset comprises a molded shell having cavities 1, 2 at each end for accommodating the transmitter and re-

ceiver capsules 4 and 5 respectively. A channel is molded along the length of the handset to receive a multiconductor cord with spaced conductors in flat arrangement, more specifically flat three conductor cord 3 which lies at the bottom of each cavity 1, 2 and passes through the handle. The rubber or plastic cover of the cord 3 is formed with a longitudinal ridge which fits into a corresponding groove in the channel and thus ensures that the cord is correctly positioned therein. The cavity 1 adapted to receive the transmitter capsule 4 has molded in its bottom two cylindrical depressions 6, 7 into which fit corresponding depending projections 8, 9 in the lower surfaces of the adapter.

The adapter comprises a molded insert as illustrated in Figs. 2 to 4 and consists of an annular base 10 formed with the depending projections or pegs 8, 9 and diametrically disposed holes 11, 12. The upper surface is provided with a pair of arcuate projections 13, 14 the function of which will be explained later. The center of the base 10 is formed with a rectilinear hole 15 provided at each corner with narrow slots 16 for accommodating the side edges of the contact members 17, 18. On each side of the hole 15 the bottom of the base 10 is formed with a line of molded teeth 19 which register with the cord 3 when the adapter is inserted in the transmitter cavity 1.

The contact members 17, 18 consist of hard metal strips the ends of which are bent over at a right-angle the depending edges being provided with a plurality of sharp prongs 20. The contact members 17, 18 are fastened to the base 10 by metal eyelets 21, 22 which are inserted in the holes 11, 12 and their lower ends spun over against the lower surface of the base member 10. The eyelets 21, 22 also secure to the base member 10 a pair of U-shaped springs 23, 24 the free arms of which extend upwards into the cavity 1.

To assemble the transmitter end, the adapter is positioned in the base of the cavity 1 with the projections 8, 9 fitted into the holes 6 and 7. The transmitter capsule 4 is then inserted in the cavity 1 and the cap 25 screwed on to the end of the handset shell. An annular projection 26 on the inside of the cap 25 engages the capsule 4 and the act of screwing on the cap 25 forces the lower part of the capsule 4 against the top of the arcuate projections 13, 14 on the adapter base 10 and at the same time causes contact to be made between the spring 23 and the capsule case and between the other spring

24 and the center terminal 36. The adapter base 10 is pressed firmly towards its seating in the base of the cavity 1 and the sharp prongs 20 of the contact members 17, 18 are caused to pierce the insulation of the cord 3 and are driven into the stranded wires of the two outer conductors. At the same time the teeth 19 are clamped against the upper surface of the cord 3 on either side of the prongs 20 thus securing the cords against movement.

Referring now to Figs. 5 to 7 the construction of the receiver end is generally similar to that of the transmitter end. The adapter shown in Figs. 5 to 7 comprises a molded block 10' formed with depending pegs 8', 9' adapted to fit into holes 6', 7' in the base of the cavity 2, and upwardly projecting cheeks 13', 14' adapted to be engaged by the receiver capsule 5 when the cap 25' is screwed home. The central hole 15' is slightly off-set from center so that the prongs 20' of the contact members 17', 18' are off-set and will pierce the centre conductor and one of the outer conductors of the cord 3. A pair of U-shaped contact springs 23', 24' and the contact members 17', 18' are fastened to the block 10' by screws 29, 30 which are screwed into the holes 11', 12'.

In assembling the receiver end, the block 10' is positioned in the receiver end cavity 2 with the pegs 8', 9' which are of different diameters entering the holes 6', 7' also of different diameters to correspond with the peg characters, the receiver capsule 5 is then inserted and the cap 25' screwed on, during which operation the capsule 5 engages the cheeks 13', 14' on the block 10' and forces the prongs 20' into the stranded wires of the centre and one outer conductor of the cord 3: at the same time electrical contact is made between the terminals 27, 28 on the receiver capsule and the springs 24' and 23' respectively.

It will be understood of course that the two pronged contact members at the receiver end might be arranged to effect contact with the two outer conductors respectively and the two pronged contact members at the transmitter end to make contact with the centre and an outer conductor depending upon the manner in which the conductors of the cord 3 are connected to the substation circuit. In this arrangement, the pegs 8', 9' of the receiver capsule adapter and their corresponding holes 6', 7' need not be dissimilar in diameters as poling would not be necessary, whereas the pegs 8, 9, of the transmitter capsule adapter and their corresponding holes 6, 7 would be of different diameters to ensure of the pronged contact members piercing the proper conductors.

What I claim is:

1. A telephone transducer comprising a supporting shell, a transducer element, a cavity in said shell for accommodating said transducer element, a cover for the cavity, a conductor cord comprising a plurality of parallel conductors, means for positioning said cord at the bottom of said cavity, a detachable connector block having mounted thereon connector members formed with sharp prongs and also having mounted thereon yielding contacts shaped so as to make contact with the electrode terminals of the transducer element when the latter is inserted in said cavity, electrical connections between said connector members and said yielding contacts, and means including the cover for forcing the said prongs of said connector members into said cord to automatically make electrical contact between said electrode terminals and said conductors when

said transducer element is seated in said cavity and for holding the yielding contacts against the electrode terminals.

2. A telephone transducer comprising a supporting shell, a transducer element, a cavity in said shell for accommodating said transducer element, a conductor cord comprising a plurality of parallel conductors, a channel in the bottom of said cavity for said conductor cord, a detachable connector block having mounted thereon a pair of connector members formed with depending sharp prongs and also having mounted thereon a pair of upwardly-extending spring contacts, electrical connections between said connector members and said spring contacts, a surface on said connector block which abuts a portion of the casing of said transducer element when the latter is inserted in said cavity said connector members and said spring contacts being so shaped and positioned that when said transducer element is forced home in said cavity said prongs are forced into said cord to make electrical contact with conductors thereof and said spring contacts make contact with the electrode terminals of said transducer element.

3. A telephone transducer according to claim 2 in which said connector block is provided with a plurality of projecting portions and the bottom of said cavity is formed with corresponding depressions to receive said projecting portions.

4. A telephone transducer according to claim 2 in which a common fastening means is provided for securing each connector member and its corresponding spring contact to said connector block.

5. A telephone transducer according to claim 2 in which the lower surface of said connector block is provided on either side of said prongs with teeth which are clamped down upon said cord when said transducer elements is forced home in said cavity.

6. A telephone transducer comprising a supporting shell, a transducer element, a cavity in said shell for accommodating said transducer element, a conductor cord comprising a plurality of parallel conductors, means for positioning said cord at the bottom of said cavity, a detachable connector block having mounted thereon connector members formed with sharp prongs and also having mounted thereon yielding contacts shaped so as to make contact with the electrode terminals of said transducer element when the latter is inserted into said cavity, electrical connections between said connector members and said yielding contacts, an abutting surface on said connector block which abuts a portion of the casing of said transducer element when the latter is inserted into said cavity, a peripheral lip on said transducer element, a seating for said lip on said supporting shell at the edge of said cavity, and a threaded cap formed with an abutment which when said cap is screwed onto said shell forces said lip against said seating, the distance from the points of said prongs to said abutting surface on said connector block being such that when said lip is forced against its seating by the act of screwing on said cap, the said prongs are forced into said cord and make electrical contact with conductors of said cord.

7. A telephone transducer comprising a supporting shell, a transducer element, a cavity in said shell for accommodating said transducer element, a conductor cord comprising a plurality of parallel conductors, means for positioning said cord at the bottom of said cavity, a detachable connector block having mounted thereon con-

necter members formed with sharp prongs and also having mounted thereon yielding contacts shaped so as to make contact with the electrode terminals of said transducer element when the latter is inserted into said cavity, electrical connections between said connector members and said yielding contacts, an abutting surface on said connector block which abuts a portion of the casing of said transducer element when the latter is inserted into said cavity, and a threaded cap formed with an abutment which when said cap is screwed onto said shell forces said transducer element and said connector block downwardly in said cavity, the distance from the points of said prongs to said abutting surface on said connector block being such that when said cap is in its screwed on position the said prongs are forced into said cord and make electrical contact with conductors of said cord.

8. A connector unit for insertion into a recep- 20

tacle having at its bottom a multiconductor cord with spaced apart conductors and inwardly-extending guides at opposite sides of said cord, a seat for a transducer element and a cap to close the receptacle and force said transducer element against said seat, said unit having cord-piercing members spaced in accordance with said conductors, means to cooperate with said guides to position said cord piercing members over said conductors, yieldable contacts connected to said cord-piercing members and positioned to cooperate with the electrodes of said transducer element, and upward projections for engagement with said transducer element whereby movement of the transducer element against its seat will force the connector unit inwardly and the cord-piercing members into engagement with said conductors.
